Robert Boale

The schedule refers to a short letter patent now making part of the laws containing a description in the name of the said Robert Boale himself of his improvement in carriages, by which the horses may be suddenly disengaged when running away; or when required, to be detached from the carriage quickly, called the safety carriage.

Be it known, that Robert Boale of the city of Washington in the District of Columbia, has made an improvement in carriages, by which the horses may be suddenly disengaged when running away; or when required, to be detached from the carriage quickly, called the safety carriage, which is described as follows:

The straight-tree is attached to the carriage by an iron fixture called a jointed-clasp, fastened to the horse post marked A, resting against the back of the carriage. This jointed-clasp is held up against the under-side of the carriage by an iron bar, a hinged-clasp, fastened to the carriage, turning on a joint or hinge secured to the under-side of the carriage. To the end of the hinged-clasp is attached an iron rod or bolt, B, with an eye at its end. This rod or bolt passes through an opening in the carriage, and has an eye, + key inserted through the eye resting on the upper-side of the bar, which, which secures the jointed-clasp from dropping. On the rod may be fixed permanently to the cross-bar projecting far enough below it to pass thro' a slot or mortise in the end of the hinged-clasp, with a sprung-key inserted through the end of the rod or bolt to prevent the hinged-clasp falling. To the end of the sprung-key is attached a cord which hangs inside of the carriage where it hangs loosely. Should the horse take fright and become uncontrollable than the cord is to be pulled suddenly which will draw the sprung-key from the eye of the rod or bolt, let fall the hinged-clasp, and with it the jointed-clasp attached to the straight-tree, and will disengage the horse from the carriage. The tongs are open in front thro' T----T----, to allow the breeches to slip off freely. This breeches is made from a single strap of leather, with wings sewed to the ends to hook over the tongs.

The shutter or hinged-clasp may have its end turned up at right angles and formed like a catch or hook, and secured by a sprung fastener to the side of the carriage; the cord being attached to the end of the sprung. The shutter may consist to hold up in a great variety of ways but the before

D. C.

described are sufficient to show the principle of my invention.

When it is desired to retain the singletree and let the horses off with the traces only, then a hinged clasp must be put on each end of the singletree with the jointed clasps secured to the ends of the traces, and the cords attached to the spring keys run through pulleys and are joined to the single cord which leads inside of the carriage.

In the two horse carriage the shutters or hinged clasps are hung on the under side of the whipple-tree, and the cords attached to the spring-keys run along on the top of the whipple-tree in a straight line; then pass around pulleys and are joined to the single cord which leads inside or outside of the carriage. The pulleys are to cause the cords to run freely and to draw the spring-keys or pins from the eyes of the rods or bolts in a straight line - An iron tube with a flange on one end is fastened to the end of the pole. over this is put a thimble having a ring on each side to which the breast straps are attached. This thimble slips off the end of the pole when the horses are disengaged. The mode of detaching the horses from the two horse carriage is similar to that described for a single horse carriage.

In a four horse carriage the leaders are disengaged from the pole in the same manner by a jointed clasp, hinged clasp, spring-key and cord, as described for a two horse carriage.

The jointed clasp may be held up against the crossbar by a pin inserted through the jointed clasp into the hind part of the crossbar to which pin the cord is attached.

The jointed clasp may also be secured by a spring fastened on the hind part of the crossbar, the cord being attached to the end of the spring.

Springs or friction bars are secured to the carriage and brought in contact with the hub in order to decrease the motion of the carriage when the horses are liberated, or before they are liberated.

This invention may be applied to field artillery, and which will enable the men to limber or unlimber the gun in less than half a minute.

It may be applied to carriages and wagons of every description, to

Ploughs, harrows, and all kinds of agricultural implements drawn by horses, when required to be taken in haste from the carriage to field &c.

A fourth piece of iron is suspended over the hind and front axles to prevent its turning on the body bolt.

What I claim as my invention, and which I wish to secure by Letters Patent, is the before described apparatus for suddenly disengaging horses from Carriages &c.

For a further illustration of my invention I refer to the Model & drawings of the same deposited in the Patent Office.

In witness whereof I have hereunto subscribed my name at the City of Washington, this tenth day of May, 1832. —
